UNITED STATES PATENT OFFICE.

GEORGE M. MILES, OF FLOWERFIELD, MICHIGAN, ASSIGNOR OF ONE-HALF TO STAND-ARD RICE COMPANY, INC., OF, HOUSTON, TEXAS.

APPARATUS FOR THE MILLING OF RICE.

Application filed April 16, 1924. Serial No. 706,938.

This invention relates to improvements in apparatus for the milling of rice according to an improved process such as set forth in my U. S. Patent No. 1,495,561, granted May 5 27, 1924.

An important object of this invention is the provision of an improved apparatus for the milling of rice which embodies hullers to loosen or break the bran from the kernel, 10 and aspirating means wherein the bran is effectively segregated from the rice kernels in such manner that the kernels will not be broken or discharged with the bran, as is sometimes the case where ordinary reels are 15 used.

A further object of this invention is the provision of novel apparatus for the milling of rice, which embodies an effective arrangement of hullers and aspirating units, with a 20 well balanced and carefully regulated suction system for the loosening and segregation of bran from the rice kernels, in a complete and satisfactory manner, without the breaking of rice, and without the discharge 25 of fragmentary kernels with the bran.

A further object of this invention is the provision of apparatus for the simple, economical, and efficient removal of bran from the rice kernels, which will render a higher 30 yield than is now possible with milling processes not practiced according to the process defined in my patent above referred to.

Other objects and advantages of this invention will be apparent during the course 35 of the following detailed description.

In the drawings, wherein similar reference characters designated corresponding parts throughout the several views.

Figure 1 is a diagrammatic representation 40 of a milling program, embodying the units and elements necessary for the practicing of my improved process.

Figure 2 is a longitudinal cross sectional view taken through a huller unit which is 45 preferably used as a part of my apparatus.

Figure 3 is a cross sectional view taken substantially on the line 3—3 of Figure 2.

Figure 4 is a sectional view taken through 50 a rotary disc aspirator which may be used as one of the aspirating units of my invention, and

Figure 5 is a cross sectional view taken

through the aspirating unit illustrated in Figure 4.

In the drawings, wherein for the purpose 55 of illustration is shown the preferred apparatus, the letters A and B may generally designate first break hullers, which receive the cargo rice from a conveyor or conduit 10, a branch of which conduit leads to each 60 of the hullers. Aspirating units C and D are provided, which are connected by means of a conveyor or conduit 12; the aspirating unit C preferably being connected by means of a conveyor or shaft 13 with the first 65 break hullers A and B. The second break hullers E and F are provided, which are preferably connected by a conveyor or shaft 15 with the aspirating unit D, for the purpose of conveying the rice to the second 70 break hullers E and F after treatment in the aspirating units C and D. After treatment in the second break hullers E and F, the rice is led respectively through a second set of aspirators, consisting of units G and 75 H; the unit G being connected with the second break hullers E and F by means of a shaft or conveyor 18. The units G and H are respectively connected by means of a shaft 20, and a shaft 21 leads from the low- 80 ermost aspirator H, for purpose of conveying the rice kernel stock to any suitable location, such as sacks, receivers, or other apparatus.

The hulling units A, B, E and F are pref- 85 erably all of the same construction, and each of the same preferably includes a casing 25, provided with a top 26 which is removably positioned thereon. Bearing in the casing 25 is a shaft 27 which supports a fluted 90 cylinder 29 in the casing. One end of the shaft 27 is preferably provided with a driver pulley 30, and at the other end of the casing 25 the shaft 27 supports a fly wheel 31. The flutes or corrugations in the cylinder 29, run as illustrated in Figure 2 of the drawings, wherein it is shown that each corrugation or flute in the cylinder consists of an intermediate straight portion 33, and the end spiral portions 34 and 35. A funnel shaped grain inlet 36 is supported by the top of the casing, to one end, and into which the rice prior to removal of bran therefrom is supplied, from the shaft 10 or

15 or a branch thereof, as is illustrated in the milling program in Figure 1 of the drawings. This grain is supplied to the cylinder 29, at the spiral ends 34 of the flutes in this 5 cylinder, and the rice is subjected to a gentle action in the cylinder, for the purpose of loosening and removing the bran from the rice kernel, as it is conveyed along the huller, incident to rotation of the cylinder 29, 10 At the opposite end of the casing 25 from the inlet funnel 36, an outlet or a discharge opening 40 is provided, adjacent the spiral portions 35 of the cylinder flutes, and with which outlet or exit opening 40 the shafts or 15 conveyors 13 or 18 communicate, to carry the grain away from the hullers, as is illustrated in the milling program in Figure 1 of the drawings. At the lower portion of the casing 25, a perforate screen 41 is supported, over which the cargo rice is moved, and through which the bran is sucked into 20 a funnel shaped member 42 which is used for coupling the huller to the suction shaft 43 of my milling program, in a manner to 25 be subsequently described.

The aspirating units C, D, G and H are to be sharply distinguished from the ordinary rice bran reels, and it is to be understood that the rice in these aspirators is not subjected to the wearing action that they receive in the conventional reel, but they are gently treated as they are vibrated or spread therein. By way of example a preferred type of aspirating unit has been illustrated 30 in Figures 4 and 5 of the drawings, which consists of a casing 50 of substantially cylindrical formation, which is arranged upon a vertical axis, and rotatably supports the vertical rod 51 axially therethrough, which 35 at its lower end supports a tray 52. The rod 51 exteriorly of the aspirator is connected for drive by suitable mechanism 53. The rice is fed into the aspirator cylinder 50 by means of a funnel shaped conduit 55, 40 so that the rice falls upon the tray 52. The stock thus falling upon the center of the revolving disc is carried incident to rotation thereof to the other edge, in a thin stream, where it is subjected to an air current from 45 below, so that the latter bran is drawn up through the air and discharged into a suitable dust collector, which in the milling program has been designated by numeral 58. The aspirator casing 50 supports the tip 59 therebelow, which is of funnel shape 50 formation, and which is connected to the casing 50 so that air may enter from adjacent the casing 50 and the tip 59. The heavier kernels, of course, fall into the aspirator 55 tip 59, and are spouted either to another aspirator, a huller, or to any desired location. The aspirator casing 50 supports the lateral extension 65, which is provided with a compartment therein subdivided by means of a 60 depending baffle 66. Adjacent the commu-

nication of the arm 65 with the top of the casing 50, a reduced communicating passageway 67 is provided, which is regulated by means of an air control member 68. In the top wall 69 of the arm or extension 65, 70 a suction shaft is connected, which communicates with the compartment of the arm 65 at the opposite side of the baffle 66 with respect to the air control 68. This suction line forms an important part of my milling 75 program, as will be subsequently described, and the lighter particles of the bran, such as dust, are lifted upwardly thereinto. The heavier particles of the bran fall by gravity through an outlet 70 at the lower 80 end of the aspirator extension arm 65, where they fall into suitable conveying means.

In connection with the first break hullers A and B, valves 90 and 91 are respectively provided in the branch conduits 92 and 93 which lead to the suction line 43, wherein a draft is pneumatically provided by means of an aspirating fan 94 of any approved kind. The aspirating fan 94 has its discharge end 95 connected with the dust collector 58, by means of a shaft 96, and the material from the dust collector 58 may be discharged into a conveyor 99 connected therewith, from whence it may be conveyed 90 to any suitable receiving box, or the like. 95

The second break hullers E and F have their funnel shaped connecting pieces 42 communicating with the suction line or conveyor 43, by means of branch lines 100 and 101 respectively; control valves 102 and 103 being provided in these lines for regulating suction through the hullers, so that the loosened branch may be properly removed, without lifting any rice kernels 100 or fragments thereof. 105

The aspirating units C and D which are connected between the first and second break hullers may respectively have suction communication with the aspirating fan 94, by means of branch conduits 104 and 105, 110 which are connected in the line or conduit 108; valves 106 and 107 respectively being provided for the aspirating units C and D, for properly controlling air suction therethrough. In analogous manner the aspirating units G and H, following the second break hullers, may be connected in the suction line 108, by means of branch conduits 110 and 111, which respectively have control valves 112 and 113 therein. 115

The lateral conveyors 115 may be provided at the discharge end of each aspirator extension arm 65, for the purpose of conveying the heavier bran and foreign material 125 to the discharge conveyor 99, and as is illustrated in the milling program.

Following the operation of the apparatus, the cargo rice is fed into the first break hullers A and B, and therein the rice 130 is agitated for the loosening of the bran

from the kernel, and a gentle air suction takes place through the housing of each of the hullers A and B, so that any loosened bran may be sucked out of the huller, in accordance with the construction and operation above mentioned. The valves 90 and 91, of course, regulate the suction which takes place through the hullers, so that none of the rice kernels or fragments thereof are lifted into the suction line. The rice is then discharged into the conveyor 13, and into the first aspirating unit C, where it is treated therein, as above mentioned, and the lighter particles of the bran and dust are sucked upwardly through the branch conduit 104, and the heavier bran gently falls through the exit at the lower end of the aspirator extension arm 65 into the conveyor 115. The rice falls from the aspirator tip, through the connecting shaft 12 into the lower aspirator unit D, and is therein treated in analogous manner for the removal of bran from the rice. The rice passes from the unit B into the second break hullers E and F, and is therein again treated for loosening any of the remaining bran which may adhere to the kernels of rice. The rice then passes successively through the aspirator units G and H, and is conveyed to any suitable location.

While the milling process shows that the fan 94 is employed for creating the desired air suction throughout the system, I contemplate, and have practiced the invention using a single aspirating fan for each aspirating unit, and for the break hullers. The use of the double aspirators between the first and second break hullers, and succeeding the second break huller enables a graduated air suction to get all of the bran segregated from the rice kernels. This treatment of the rice is a novel departure from the conventional treatment of rice in reels. The disadvantages of using rice reels is well known to those skilled in the art to which this invention relates, and the breaking of these reels is a quite common occurrence, is very wearing on the rice, and entails a huge maintenance cost. In my process, using the apparatus described, from 30 to 70% of the bran may be removed by suction at the first and second break hullers, and the remaining bran is removed at the aspirating units, so that I obtain a full and complete separation of the bran from the rice kernels, without losing any of the latter.

While I have shown and described a preferred type of huller and aspirator, it is to be distinctly understood that other types of hullers and aspirators may be used, utilizing the combination of apparatus set forth in my milling program, in order to practice the process as defined in my patent above mentioned.

Various changes in the shape, size, and arrangement of units for the practising of this invention may be made to the arrangement set forth in my milling program, without departing from the spirit of this invention or the scope of the claims.

I claim:

1. In an apparatus for the milling of rice the combination of a huller, an aspirator, means connecting the huller with the aspirator, suction means connected with the huller for removal of bran therefrom, and adjustable suction means for the aspirator for removing bran from the rice therein, the suction means of the aspirator being independently variable with respect to the suction means of the huller.

2. In apparatus for the milling of rice the combination of a huller, a first aspirator unit, means for passing rice from the huller to the first aspirator unit, a second aspirator unit, means for passing rice from the first aspirator unit to the second aspirator unit, and variable suction means for each of said aspirator units independently operable with respect to each other.

3. Apparatus for rice milling comprising first and second break hullers, a series of aspirating units in connected relation intermediate said first and second break hullers, and succeeding said second break hullers, and means providing a variable suction through said hullers and aspirators.

4. Apparatus for milling rice comprising a first break huller, an aspirator connected with the first break huller to receive rice therefrom, a second break huller, a second aspirator connected with the second break huller to receive rice therefrom, and means for creating a suction through said aspirators to remove bran from the rice kernels.

5. Apparatus for milling rice comprising first break hullers, second break hullers, a plurality of aspirator units in successively connected relation between the first and second break hullers, and means for creating a suction through the aspirators.

6. Apparatus for milling rice comprising first break hullers, second break hullers, a plurality of aspirator units in successively connected relation between the first and second break hullers, and means for creating a suction through the aspirators and through the first and second break hullers.

7. Apparatus for the milling of rice comprising first break hullers, an aspirating unit connected with said first break hullers, a second aspirating unit connected with the first aspirating unit to receive rice therefrom, second break hullers, means connecting the second break hullers with the second aspirating unit to receive rice therefrom, and aspirating means connected with the second break hullers to receive rice therefrom.

8. In apparatus for the milling of rice the

- combination of first break hullers, second break hullers, aspirating means connected between the first and second break hullers, aspirating means connected with the second break hullers to receive rice from the second break hullers, suction shafts connected with said aspirating means, and valve means in said suction shafts for variably regulating suction through said aspirating means.
- 10 9. In an apparatus of the class described the combination of a first break huller, a second break huller, an aspirator unit connected intermediate said first and second break hullers, an aspirator unit succeeding said second break huller and connected there-
- 15 with, suction means, and valve means for variably regulating communication of said suction means with said aspirator units.
10. In an apparatus of the class described the combination of a first break huller, a second break huller, an aspirator unit connected intermediate said first and second break hullers, an aspirator unit succeeding said second break huller and connected therewith, suction means, and valve means for variably regulating communication of said suction means with said aspirator units and with said first and second break hullers.

GEORGE M. MILES.
